MILK BOTTLE CAP

Herman William Budan, Los Angeles, Calif.

Application December 2, 1944, Serial No. 566,282

2 Claims. (Cl. 215—38)

1

My invention relates to a cap for milk and other bottles and may be used as desired for the only cap required for covering a bottle. However, a prime use for my bottle cap is for capping a milk bottle after the ordinary disk seal cover has been removed from a milk bottle.

The general custom for the delivery of milk for household consumption is to use glass bottles, the nozzles of which are provided with an inward seat into which there is pressed a flat disk of pasteboard or other suitable material which is held in place by frictional contact within the nozzle.

The above indicated construction leaves a little circular cavity above the disk into which there is opportunity for the accidental accumulation of foreign matter, and to avoid this there is provided different means for covering the top of the bottle with an overriding hood made of a variety of materials, chiefly paper of some sort.

This outside hood in most cases acts only as a protection against the entrance of foreign matter to the interior of the bottle in which milk is stored, and does not of itself form any real tight seal which will hold the milk in the bottle if the bottle was tilted on its side or was upset in any manner.

The pasteboard disk seal commonly used in the nozzle of glass milk bottles is pressed in so tightly that when its removal takes place, that disk is damaged to the extent that it ceases to be a tight closure of the bottle against leakage of the contents of the bottle when the bottle is upset and that disk being the only cover then of the bottle.

My cap not only provides for a tight closure of the top of the bottle but it also provides a means whereby the disk cap, commonly used, may be engaged and lifted from the bottle using my cap as the instrument for contacting and lifting the disk cap from the bottle.

An object of my invention is to provide a cap, preferably of metal or other materials which is sufficiently stiff and yet elastic in nature that it may be sprung onto the top of the bottle and automatically lock itself on the bottle for a complete closure of the bottle.

Another object of the invention is to provide a cap of material having a series of spring fingers adapted to extend down on the outside of the

2

bottle top and clamp my cap into place and those spring fingers constructed in peculiarly desirable shapes, not only for holding my cap in place but also to furnish means for using my cap as an instrument in removing another cap from the top of the bottle.

Another object of my invention is to provide a cap which furnishes the advantages above mentioned together with an improved appearance and desirable shape for handling and applying my cap to bottles.

Reference will be had to the accompanying drawings in which

Figure 1 is a perspective view of the top of a bottle with one form of my cap applied thereto.

Figure 2 is a vertical section on line 2—2 of Figure 1.

Figure 3 is a perspective view indicating how my cap is preferably applied to the top of a bottle but it may be applied by vertical movement also.

Figure 4 is a perspective view indicating the method of using my cap as an instrument in removing an ordinary disk cap from the top of a bottle.

Figure 5 is a vertical section of the top of a bottle showing a modified form of the cap.

Figure 6 is a plan view of the top of my cap, as placed on a bottle showing a modified form of the clasping fingers of my cap.

Figure 7 is a modified form of one of my clasping fingers.

In the drawings the simplest form of my cap is indicated by Figures 1 to 4 inclusive. This cap is provided with the upwardly embossed circular area A offset at a shoulder 3 to stiffen the bearing seat portion 4 which contacts tightly the top nose of nozzle 5 of the bottle 6. This bottle is substantially the standard milk bottle for household delivery supply having the seat 7 for the ordinary disk seal cap, one of which is indicated by 8 in Figure 4. The bottle 6 is provided with a reinforced ring nozzle 9.

The seat portion 4 is provided with a narrow flange 10 adapted to fit snugly to the shape of the top of the nozzle 5 of the bottle.

On the opposite sides of the flange 10 there extends downwardly the clasping fingers 11 and 12. These clasping fingers are of spring character and clasp snugly to the portion 9 of the nozzle. Each of the clasps 11 and 12 are pro-

vided with small holes 13 which may be used for hanging the cap on a nail or a hook for supporting the cap when it is not in use on a bottle.

In the ordinary use of my cap as in common commercial practice, the milk will be supplied to the user being capped only by a common pasteboard cap indicated by 8 in Figure 4, and mounted in place on the seat 7 of Figure 2.

The first act of the user in drawing some milk from the bottle is to remove the disk seal cap 8. Many of these disk caps are provided with a wire staple hook on one side thereof, or a portion of the cap has been cut asunder to provide a small lip section 14, see Figure 4. It is a bit troublesome to lift out this disk with the ordinary fingers, even though the disk may be provided with a wire staple or the lip 14.

I provide my clasping finger 11 with an extending point 15 which may be used as indicated by Figure 4 as an instrument whereby the point 15 may be pressed into the top of the disk cap and is thereby lifted from its seat in the bottle.

The clasping fingers 12 are shown as wanting the points 15 as shown for the clasping fingers 11. Yet withal the ends of these fingers 12 may be used to engage the lip 14 or a wire staple into the disk 8.

A modified form of my fingers 11 and 12 is indicated in Figures 6 and 7. This modified form is provided with the clasp body 16, see Figures 6 and 7, which are provided not only with the extending point 15 but is also provided with the outwardly curled over edges 17' which act as guides in shoving my cap transversely across the top of the bottle in placing the cap on the bottle. The sheet material of the clasp body 16 on the edge opposite the curved edges 17 is recessed in an edgewise manner thereby providing a hook shaped projection 18. This hook shaped projection 18 has its point directed toward the cap and may be used as desired in place of the extending point 15 in lifting a disk cap 8 from the top of a milk bottle.

In removing a conventional milk bottle cap an advantage results from using the hook-shaped projection 18 of the ear 16 in cooperation with the central downwardly extending point 15, because, when the hook 18 has been inserted into the flap or lip 14 of the bottle cap, as indicated in Fig. 7, said point 15 may then be indented into the cap and used as a fulcrum to remove the cap by a prying-off movement, rather than by bodily withdrawing the latter in such a sudden manner as would be likely to cause an cut-splash of milk. When it is so used, the widened part of the ear 16 superjacent to the point 15 provides shoulders which prevent too deep a penetration of the point 15 into the cap 8 and assist in prying off the latter. The out-curved parts 17' are also useful as finger-holds to assist the operator in lifting the metallic cap from the bottle.

In the normal use of my cap it will be slid transversely across the top of the bottle as indicated by Figure 3 by moving toward the left the cap shown at the right of Figure 3 and sliding it transversely across the top of the bottle, in which movement the flange 10 of the cap slides over the top 5 of the nozzle and the fingers 11 and 12 will spring outside of the portion 9 of the bottle, and when the movement is complete, bringing the cap concentric with the nozzle of the bottle and the spring action of the fingers will cause the cap to move down snugly on to the top of the nozzle 5 making a complete seal of my cap to the bottle.

However, the cap may be mounted directly over the top of the bottle and pressed vertically downward causing the spring fingers to snap into place and hold the cap to the bottle.

5 The modified form of the cap as shown in Figure 5 is provided with an inwardly embossed seat 19 which is provided with an overlapping flange 20 on the inside of which is mounted a ring 21 of a gasket character. The lower skirt 22 of the overlapping flange 20 has been slitted up part way in sections to permit a springing action of the skirt in clamping the outside nozzle of the bottle as this cap is applied to the bottle.

For convenience in handling this cap of Figure 5, there is provided the hand hold knob 23.

As and when desired the cap as shown by Figure 5 may be provided with a pointed clasping finger 24 as shown in dotted lines in Figure 5. This pointed finger 24 will be used in prying up a disk cap as indicated in Figure 4.

20 What I claim is:

1. In a cap of the class described, a central area surrounded by a circular seat portion, a circular flange extending downwardly from the outer edge of said seat portion, two diametrically opposite spring ears each having side edges, said ears extending downwardly from said flange, at least one of said ears having in one of its side edges an arcuate recess which produces a hook with a point suited to hooking onto the finger-hold flap of a conventional milk bottle cap, said point being directed toward the aforesaid circular flange, said ear having also a central downwardly directed point portion to indent or puncture a conventional milk bottle cap, the latter point portion affording an anchored fulcrum point for use in prying off said conventional cap when the aforesaid hook is applied under the finger-hold flap thereof, said ear which carries said downwardly directed point portion being widened superjacent to said downwardly directed point portion thus affording stop shoulders which prevent more than a slight penetration of the cap by the latter point portion when used as a fulcrum, as aforesaid.

2. In a cap of the class described, a central area surrounded by a circular seat portion, a circular flange extending downwardly from the outer edge of said seat portion, two diametrically opposite spring ears each having side edges, said ears extending downwardly from said flange, at least one of said ears having in one of its side edges an arcuate recess which produces a hook with a point suited to hooking onto the finger-hold flap of a conventional milk bottle cap, said point being directed toward the aforesaid circular flange, said ear having also a central downwardly directed point portion to indent or puncture a conventional milk bottle cap, the latter point portion affording an anchored fulcrum point for use in prying off said conventional cap when the aforesaid hook is applied under the finger-hold flap thereof, said ear which carries said downwardly directed point portion being widened superjacent to said downwardly directed point portion thus affording stop shoulders which prevent more than a slight penetration of the cap by the latter point portion when used as a fulcrum, as aforesaid, that edge portion of the aforesaid cap-removing ear which is opposite to its cap-removing hook portion being outwardly curled over in relation to the center of the first recited cap, the diametrically opposite ear having a correspondingly outwardly curled over portion, so that 70 said curled ear portions cooperate when engaged.

with opposite sides of the mouth portion of the milk bottle to guide the cap toward its applied position.

HERMAN WILLIAM BUDAN.
